Fraser, Funk & Myers

UNITED STATES PATENT OFFICE.

PAUL MAUSER, DECEASED, LATE OF OBERNDORF-ON-THE-NECKAR, GERMANY, BY FRIEDRICH EICHHORN, ADMINISTRATOR, OF OBERNDORF-ON-THE-NECKAR, GERMANY, ASSIGNOR TO WAFFENFABRIK MAUSER AKTIENGESELLSCHAFT, OF OBERNDORF-ON-THE-NECKAR, GERMANY, A CORPORATION OF GERMANY.

FIREARM.

1,217,974.

Specification of Letters Patent.

Patented Mar. 6, 1917.

Application filed August 20, 1915. Serial No. 46,582.

To all whom it may concern:

Be it known that PAUL MAUSER, deceased, a subject of the King of Wurtemberg, and prior to his death residing at Oberndorf-on-the-Neckar, in the Kingdom of Wurtemberg, Germany, invented new and useful Improvements in Firearms, of which the following is a full, clear, and exact specification.

10 The present invention relates to a breech arrangement for fire-arms with return spring. In such breech arrangements the return spring is generally disposed in such a manner within the breech casing, that it forms 15 an obstruction in dismantling the breech. According to the present invention this disadvantage is obviated by the spring being disposed in such a manner in the lid of the casing, that it is removed together with the 20 said lid when the latter is taken off.

In the drawing an embodiment of the present invention has been exemplified. Figure 1 is a vertical longitudinal section through a breech embodying the invention, 25 and showing the respective parts. Fig. 2 is a plan of the lid, removed, seen from below. Figs. 3 and 4 are rear views of the casing with the bolt *c* in two different positions, respectively.

30 The return spring *S* is disposed in a sleeve-like enlargement *k*¹ of the breech piece *k*, into which on the breech being opened, a sleeve *g* provided in the lid *b* of the breech casing *h* will enter, the said 35 sleeve *g* surrounding the spring. In this sleeve *g* a rod *e* is disposed within the spring, which rod moves in a sleeve *r*, which bears with its forward, flanged end against the bottom of the enlargement *k*¹ of the breech 40 piece.

The lid *b* is held to the casing *h* by means of a swiveling bolt *c*, which pivots on a pin *b*¹ in the lid, and which has a nose *c*¹ which engages in a groove *h*¹ in the casing. 45 This swiveling bolt is, furthermore, provided with a groove *c*² curved to a circular line, which is bordered on both sides by webs. At the one end of the groove, at *c*³, these webs have been cut away, so that the rod *e* 50 may be, at this point, introduced with its rear head into the groove. Behind the head the rod *e* is reduced at *e*¹, in which reduc-

tion the webs of the groove *c*² engage, so that the rod *e* is thereby held to the lid *b*. The nose *c*¹ and the groove *c*², *c*³ of the 55 swiveling bolt are so arranged, that the rod *e* is held by the webs of the groove *c*² when the nose *c*¹ is outside of the recess *h*¹ of the casing, that is when the lid of the casing is disengaged. In consequence thereof, 60 when the lid is removed from the casing by the lid catch *c*¹ being disengaged, the rod *e* is simultaneously coupled to the lid, so that when the lid is removed from the casing, also the rod *e* is removed with it. With 65 the sleeves *r* and *g* coupled to the rod *e* and the spring *s* disposed between the said sleeves the sleeves and rod and spring are removed from the casing. The breech bolt is, then, free and is no more under the action of the spring, so that the further dismantling of the breech is not obstructed. 70

I claim:

1. A fire arm comprising a frame, a barrel, a breech piece, a closing spring therefor, said 75 frame having a chamber in which said breech piece slides, and an immobile lid over said chamber and separable from the barrel, frame, and breech piece, said lid having means for fixing said closing spring 80 thereto, whereby it may be removed with said lid.

2. A fire arm comprising a frame, a barrel, a breech piece, a closing spring therefor, said frame having a chamber in which 85 said breech piece slides, an immobile lid over said chamber and separable from the barrel, frame, and breech piece, a telescoping rod in said spring, said rod having means for limiting the extension of said 90 spring and means on the cover for fixing said rod thereto.

3. A fire arm comprising a frame, a barrel, a breech piece, a closing spring therefor, said 95 frame having a chamber in which said breech piece slides, and an immobile lid over said chamber and separable from the barrel, frame, and breech piece, said lid having a bolt adapted to fix said closing spring thereto and for fixing said lid to the frame. 100

4. A fire arm comprising a frame, a barrel, a breech piece, a closing spring therefor, said frame having a chamber in which said breech piece slides, an immobile lid over

said chamber, a telescoping rod in said spring, said rod having means for limiting the extension of said spring, and a bolt *c* pivotally mounted on said lid, and having 5 means for engaging said rod and means for locking said lid to the frame.

5. A fire arm comprising a frame, a barrel, a breech piece, a closing spring therefor, said frame having a chamber in which said 10 breech piece slides, an immobile lid over said chamber, a telescoping rod in said spring, said rod having means for limiting the extension of said spring, and a bolt *c* pivotally mounted on said lid, and having 15 means for engaging said rod and means for

locking said lid to the frame, said means for engaging said rod being inoperative when said means for locking the lid to the frame are operative, and being operative to engage said rod when the means for locking the lid 20 are in unlocking position.

In witness whereof, I have hereunto signed my name in the presence of two subscribing witnesses.

FRIEDRICH EICHHORN,
*Administrator of estate of Paul Mauser,
deceased.*
